UNITED STATES PATENT OFFICE

152,089

DESIGN FOR A GRAND PIANO

Elwood D. Kapphan, Fort Lauderdale, Fla., assignor of one-half to Edwin B. Goldsmith, Pittsburgh, Pa.

Application May 4, 1946, Serial No. 129,309

Term of patent 14 years

Cl. D56—9)

To all whom it may concern:

Be it known that I, Elwood D. Kapphan, a citizen of the United States, residing at Fort Lauderdale, county of Broward, and State of Florida, have invented a new, original, and ornamental Design for a Grand Piano, of which the following is a specification, reference being had to the accompanying drawing, forming part thereof.

In the drawings:

Fig. 1 is a perspective view of a grand piano, showing my new design; and

Fig. 2 is a perspective view from the opposite side of that shown in Fig. 1.

The upper parts of the supporting legs at the rear of the piano which are hidden by the body of the piano in Fig. 2 have the same configuration as those shown at the front sides of the piano as in Figs. 1 and 2.

I claim:

The ornamental design for a grand piano, substantially as shown and described.

ELWOOD D. KAPPHAN.
